UNITED STATES PATENT OFFICE.

KING A. HARVIE, OF PROVIDENCE, RHODE ISLAND, ASSIGNOR TO WEAR WRENCH COMPANY, A CORPORATION OF MASSACHUSETTS.

WRENCH.

1,119,694.

Specification of Letters Patent.

Patented Dec. 1, 1914.

Application filed February 12, 1913. Serial No. 747,956.

To all whom it may concern:

Be it known that I, KING A. HARVIE, a citizen of the United States, residing at Providence, in the county of Providence and State of Rhode Island, have invented certain new and useful Improvements in Wrenches, of which the following is a specification.

The invention relates to pipe wrenches and has for its object to provide improved means for facilitating the action of the wrench in adapting itself to pipes and other work of varying sizes, and to increase the economy and efficiency of construction for marketable purposes.

Other objects and advantages should be readily apparent by reference to the following description taken in connection with the accompanying drawings, and it will be understood that modifications in the specific details of construction falling in the scope of the appended claims may be made without departing from or exceeding the spirit of the invention.

Figure I represents a rear view shown partly in section at the pivot. Fig. II is a perspective view. Fig. III shows one side of the rotary jaw. Fig. IV shows the other side of the rotary jaw. Fig. V shows the pivot pin. Fig. VI shows the spring for the rotary jaw. Fig. VII is a partial section showing the attachment of the fixed jaw to the wrench.

Referring to the drawings, in which corresponding parts are represented by the same reference characters, an eccentric rotary cam jaw 1, the gripping surface of which is preferably not corrugated or cut with teeth, is pivoted in the recessed handle 2 on the pivot 3. The engaging face 4 of the rotary jaw is eccentric to the pivot 3 and approaches or retreats from the fixed jaw 5 in accordance with the direction of its movement on the pivot 3.

In a circular recess 6 (see Fig. IV) surrounding the pivot on one side of the rotary jaw is placed the spiral spring 7, having one end engaged in the recess 8 in the rotary jaw, and the other end held in the recess 9 in the handle. This spring is wound in such manner that a rotation of the rotary jaw away from the fixed jaw will set up a tension in the spring tending to return the rotary jaw back toward the fixed jaw. A second recess 8' in the bottom of recess 6

provides clearance space for the spring when the end 9 is being inserted in or removed from the receptacle 9' in the handle. The rotary jaw 1 also has the recess 10 (Fig. IV) adapted to lighten the construction without weakening it unduly for service. The reverse side of the rotary jaw has the recess 11 for lightening purposes, and there is also a transverse recess 12 through the facial wall of the rotary jaw adapted to admit a pin 16 (Fig. I) in the wall of the handle. This pin acts as a limit stop for the rotary cam, being so positioned that it will engage the edge of the internal boss 11² at the points 11', acting thus as a limit stop at both ends 70 and determining the travel of the rotary jaw.

The fixed jaw 5 consists of a channel box jacket 13 (Fig. VII) of hardened material having cut teeth 14 in its gripping face and tapped, riveted, or otherwise secured to its supporting projection or stud 15 on the handle 2.

In operation, which is extremely simple, the rotary jaw is pulled back away from the fixed jaw against the tension of the spring. The fixed jaw is then brought up against the pipe or object to be grasped and the rotary jaw released, the spring causing the rotary jaw to return toward the fixed jaw until it engages the other side of the pipe or the work to be grasped. The handle of the wrench is then grasped as in the ordinary pipe wrench, the pull on the handle tending to increase the pressure between the work and rotary jaw, the work being grasped firmly and carried around in the jaws.

It will be noted that in this wrench there are no teeth at all on the rotary jaw; this is of prime importance both in operation and manufacture. It obviates a great deal of the usual scoring of the pipe section, due to the slip of the jaws on the pipe, the pipe usually not only being marked by the teeth but scored in long, deep scratches by the teeth as they slide around the pipe. Where teeth are cut on the rotary jaw it is necessary to make this jaw of material in which the teeth can be cut to a biting edge and of sufficient hardness to stand the constant usage, making it thus so difficult and expensive as to be mechanically impractical. The rotary jaw of this wrench may be pressed or cast easily, efficiently and inexpensively. The provision of the spring to 110

bring the rotary jaw into engagement with the work saves the use of one hand and enhances its facility of operation to a wonderful extent, making the action practically 5 automatic. It also prevents initial slip on the pipe. My method of making the removable fixed jaw cheapens the manufacture, at the same time increasing the clutching efficiency to a maximum, as the best hardened mate- 10 rial may be used and the teeth accurately and evenly cut thereon. With the exception of the wrought channel section 13, the whole wrench if desired may be cast economically and to best advantage.

15 Having now described my invention, that which I desire to cover by Letters Patent is:

20 1. In a wrench, in combination with a handle having a fixed jaw, a rotary jaw pivoted on the handle and having an internal depression on one side and a slot 25 through the facial walls transverse to the internal depression and a stud on the handle adapted to enter the internal recess through the slot and to engage a boss in the internal recess at determined points to limit the travel of the rotary jaw about its pivot.

25 2. In a wrench, in combination with a handle having a fixed jaw, a rotary jaw pivoted on the handle having an internal de- 30 pression, a transverse slot through the side

walls to the depression and a counter-bore around the pivot, a stud in the handle adapted to enter the internal depression through the transverse slot in the walls of the rotary jaw and to engage a boss in the depression at determined points and act as a stop to limit the movement of the jaw about its pivot, and a spiral spring in the counter-bore surrounding the pivot adapted to rotate the jaw on its pivot.

3. In a wrench in combination with a handle, a fixed jaw on the handle, a rotary jaw pivoted on the handle having a spiral gripping face eccentric to the pivot, a counterbore around the pivot on one side, an internal depression on the other side with a transverse inlet through the walls leading to the depression, a spring in the counterbore around the pivot and a stud on the handle adapted to enter the internal depression of the rotary jaw through the transverse inlet and engage stops in the internal depression at determined positions to limit the travel of the rotary jaw on its pivot.

40 In testimony whereof I affix my signature 45 in presence of two witnesses.

KING A. HARVIE.
